US00D546840S

(12) **United States Design Patent** (10) **Patent No.:** **US D546,840 S**
Sinders et al. (45) **Date of Patent:** **** Jul. 17, 2007**

(54) **MULTI-COMPONENT DISPENSING APPARATUS**

(75) Inventors: **Steven R Sinders**, Mooresville, IN (US); **Jonathon R. McMichael**, Danville, IN (US)

(73) Assignee: **GlasCraft, Inc.**, Indianapolis, IN (US)

(**) Term: **14 Years**

(21) Appl. No.: **29/257,654**

(22) Filed: **Apr. 7, 2006**

(51) **LOC (8) Cl.** **15-02**

(52) **U.S. Cl.** **D15/9**

(58) **Field of Classification Search** **D15/7-9; D23/232, 231; 417/359, 415-416, 410.1, 417/321, 265, 405**

See application file for complete search history.

(57) **CLAIM**

We claim the ornamental design for multi-component dispensing apparatus, as shown and described

DESCRIPTION

FIG. 1 is a perspective view of a multi-component dispensing apparatus including our invention;

FIG. 2 is a front view of the apparatus;

FIG. 3 is a left side view of the apparatus;

FIG. 4 is a back view of the apparatus;

FIG. 5 is a right side view of the apparatus;

FIG. 6 is a top view of the apparatus; and,

FIG. 7 is a bottom view of the apparatus.
